UNITED STATES PATENT OFFICE

ROBERT F. BRACKE, OF CHICAGO, ILLINOIS, ASSIGNOR, BY MESNE ASSIGNMENTS, TO LYNN A. WILLIAMS, OF EVANSTON, ILLINOIS, AND CLIFFORD C. BRADBURY, OF GLENCOE, ILLINOIS, AS TRUSTEES

CARBURETOR

Application filed March 4, 1931. Serial No. 520,032.

My invention relates to carburetors and more particularly to carburetors for use in connection with two cycle motors.

One of the objects of the present invention 5 is the provision of a carburetor which has good volumetric efficiency, that is large enough to permit the motor to produce its maximum horse power without sacrificing any performance or smoothness in the lower 10 or part throttle range where the amount of fuel and air delivered by the carburetor is relatively small.

A further object of my invention is the provision of means for providing maximum 15 atomization and breaking up of the fuel to permit easy starting, good economy, and good distribution where a plurality of cylinders are fed from a single device.

A further object of my invention is the 20 provision of means for utilizing a plurality of efficient Venturi tubes for the purpose of delivering sufficient fuel for all engine demands and for thoroughly atomizing the fuel under a comparatively low mixing 25 chamber depression.

The invention further consists in certain 30 novel features of construction, combinations and arrangements of the several parts whereby certain important advantages are attained as will hereinafter be more clearly set forth in connection with the accompanying drawings showing one form of my invention and in which

Fig. 1 is a plan view of a carburetor em- 35 bodying the principles of my invention, and

Fig. 2 is a sectional view taken on the line 2-2 of Fig. 1 looking in the direction indicated by the arrows.

Fig. 3 is a transverse sectional view taken 40 along the line 3-3 of Fig. 2 looking in the direction indicated by the arrows, and

Fig. 4 is a view partly in elevation and partly in section showing the idling system 45 of the carburetor and the adjustment therefor.

Similar characters of reference refer to similar parts throughout the several views.

The carburetor here shown is designed particularly for use with two cycle outboard motors in which a mechanically operated 50 valve is used between the carburetor and the crankcase of the motor for the purpose of admitting to the crankcase as much charge as is possible for the greatest power output.

Referring first to Fig. 2, 5 designates the 55 carburetor body arranged to form the mixing chamber 6 and the flange 7, the latter being arranged for attachment to the rotor housing or crankcase of the motor. Extending vertically through the housing 5 is a throttle 60 shaft 8 carrying the usual throttle plate 9 and a throttle lever 10. Extending parallel with the throttle shaft is a second shaft 11 carrying a plate 12 and hand lever 13, this combination forming the choke arrangement 65 of the carburetor. An air horn 14 is attached to the intake end of the carburetor and is provided with a weather cap 15 extending over the horn in a manner to prevent water from splashing into the carburetor during 70 the operation of the device.

Interposed between the throttle and choke plates 9 and 12 respectively and located in the mixing chamber of the carburetor is a large Venturi tube 16 which, as shown in 75 Fig. 3, is slotted at 16'. The outside diameter of this large Venturi tube is slightly more than the inside diameter of the mixing chamber. In the process of assembly the large Venturi tube 16 is compressed radi- 80 ally and then inserted to its proper place in the mixing chamber. Upon being released the tube springs outwardly to assume its original shape and size and thereby clings tightly to the inner wall of the body 5 and 85 thus prevents rattling of the parts during operation.

Extending through the carburetor body 5 as most clearly shown in Fig. 3 are two primary Venturi tubes 17 and 18 each having 90

its air entrance end 19 in direct communication with the chamber 20 formed by the cover 21. The chamber 20 has communication with atmosphere through opening 22 5 shown in Fig. 2. The exit end 23 of each of the primary Venturi tubes extends into the mixing chamber of the carburetor and as shown in Fig. 3 the two tubes are arranged one on each side of the center line of the 10 carburetor. Each of the primary Venturi tubes 17 and 18 is provided with a throat 24 having a series of fuel jets 25 therein communicating between the throat of the Venturi and the annular chambers shown at 26. 15 Extending transversely through the body 5 and the annular chambers 26 is the fuel passage 27 communicating with the vertical passage 28 in turn communicating with the passage 29 extending into the float chamber 20 30 of the carburetor. The upper end of the passage 29 is provided with a brass seat 31 arranged to cooperate with the main needle valve 32 preferably made of stainless steel or some other noncorrosive material. The 25 needle valve 32 has a serrated head 33 arranged for cooperation with a spring pressed detent 34 mounted in the cover 21.

From the description thus far described it will be apparent that all of the fuel delivered from the float chamber 30 to the primary Venturi tubes 17 and 18 can be controlled by the needle valve 32.

Extending through the floor of the float chamber 30 and preferably cast therein is a 35 brass insert 35 provided with a float valve seat 36 arranged to cooperate with the float valve 37 carried by the float pin 38. 39 designates a float preferably made of cork and attached to the pin 38 at the proper height 40 by means of the clip shown at 40. The upper end of the float pin 38 extends loosely through the cover 21, this bearing forming a guide to keep the float mechanism in alignment for proper operation. The lower end 45 of the brass insert 35 is threaded as shown to cooperate with the screw 41 arranged to secure the strainer housing 42 to the underside of the float bowl. This strainer housing is most clearly shown in Fig. 3 and has the 50 upper surface 43 chamfered to press against the fibre, cork or other soft material gasket shown at 44. The fuel intake for the strainer housing is shown at 45 arranged to feed fuel to the underside of the strainer 46. 55 This strainer is preferably made up of brass or copper wire mesh and is shaped so as to bear against the lower end of the brass insert 35 and the chamfered surface 43 of the strainer housing when the parts are assembled. The screw 41 may be provided with a cotter pin or wire 47 to prevent the disassembling of this screw from the strainer housing when the housing is removed for the purpose of cleaning the strainer. 60

65 Referring now to the idling system of the

carburetor which is most clearly shown in Fig. 4, 48 designates a fuel passage extending between the float chamber and the vertical passage 49 terminating at its upper end in the threaded portion 50 into which is 70 screw threaded the idle plug seat 51. This piece 51 is preferably made of brass and is provided as shown with the seat 52 and the transverse openings 53. Cooperating with the seat 52 is a needle valve 54 extending 75 downwardly through the housing 21 and arranged for cooperation with a spring pressed detent similar to the detent 34 used on the main needle valve.

The transverse openings 53 have communication with the annular chamber 55 which in turn has communication with atmosphere through the passage shown in dotted lines at 56. The annular chamber 55 also communicates with the vertical passage 57 in turn communicating with the horizontal passage 58 running longitudinally along the side of the mixing chamber 6. The outer end of the passage 58 communicates with the two holes 59 and 60 extending into the mixing chamber, these holes being so arranged that when the throttle is closed or nearly closed as for the lowest idle the opening 59 is disposed on the engine side of the throttle and the opening 60 on the mixing chamber side thereof.

In this throttle position the comparatively high manifold suction of the engine at idle is communicated through the opening 59 into the passage 58 which results in air being taken in from the mixing chamber 100 through the opening 60. A suction or reduction of pressure is also provided in passage 57 and annular chamber 55 resulting in the intake of air through the passage 56 and the delivery of fuel from the passage 49 105 through the valve seat 52 and into the annular chamber 55, the amount of fuel delivered of course depending upon the needle valve setting. The air intake passage 56 and annular chamber 55 are located above the 110 normal level of the fuel as shown in dotted lines in Fig. 3 so that when the motor is standing idle there can be no tendency for the fuel to siphon out of the float chamber through the idle system and into the mixing chamber through the holes 59 and 60.

The operation of the carburetor embodying my invention as above described is as follows: In starting the motor the choke plate 12 is closed and the throttle 9 opened to about 115 one quarter open position. The main needle valve 32 is opened about one turn as is the idle needle valve 54. The motor is then cranked to produce a comparatively high suction or depression in the mixing chamber 6 which results in a high velocity air flow through the two primary Venturi tubes 17 and 18. This high velocity air flow produces a high suction or reduction of pressure in the throats 24 of the Venturi tubes and causes fuel to flow 120

from the float chamber 30 through the various passages of the high speed system and through the jets 25 in the primary Venturi tubes where the fuel is mixed with the high

5 velocity air stream. This rich mixture of fuel and air is then delivered by the Venturi tubes into the mixing chamber 6 of the carburetor from which it is drawn into the crankcase of the engine.

10 Upon starting of the motor the choke is opened to its full open position as shown in Fig. 2 and the main needle valve 32 given its proper setting for best performance at wide open throttle position. The throttle 15 is then closed or nearly closed for slow running and the idle needle 54 adjusted in or out for the best hitting at this throttle position.

Because of the arrangement of the primary 20 Venturi tubes it is possible to obtain sufficient suction at the throats of the Venturi tubes for the delivery of the proper amount of fuel for all engine demands even though the mixing chamber 6 is made comparatively 25 large and therefore has a comparatively low suction or reduction of pressure during the operation of the motor. By the arrangement of Venturi tubes as shown I am enabled to multiply the comparatively low suction of 30 the mixing chamber to a point where proper fuel delivery is assured.

Attention is also called to the fact that the 35 Venturi tubes 17 and 18 are arranged to deliver downwardly so that there is no loss in efficiency as would be the case if the Venturi tubes delivered up or horizontally.

Another feature of the invention is the 40 fact that the Venturi tubes 17 and 18 deliver fuel into the mixing chamber of the carburetor at right angles to the air flow. This arrangement results in a thorough breaking up or atomizing action of the fuel in the mixing chamber and tends toward good economy and good motor performance. The symmetrical location of the nozzles 17 and 18

45 with respect to the mixing chamber 6 as shown in Fig. 3 aids materially in the proper atomization and distribution of the comparatively rich mixture delivered by the

50 Venturi tubes. By the use of two Venturi tubes the primary mixture is discharged into the secondary air stream in two separate and distinct streams each representing a proportionate amount of the quantity delivered for 55 any position of the throttle thereby distributing the mixture across the entire secondary air stream instead of a portion thereof which is the case where a single common type of jet or where a single Venturi tube is used.

60 While I have illustrated and described my invention as applied to two cycle motors of a certain type it is to be understood that certain features of this invention may be applied for use in connection with various types 65 of motors and other types of carburetors

without departing from the spirit and scope of this invention.

I claim:

1. In a carburetor, having a mixing chamber through which a stream of secondary air 70 is adapted to pass, a pair of suction multiplying Venturi tubes extending into said chamber and terminating therein and constituting the primary air inlet of the carburetor, said tubes being located symmetrically with respect to a diameter of the mixing chamber, a fuel chamber, a passage interconnecting the fuel chamber and throats of said Venturi tubes whereby fuel may be drawn into the primary air stream from said fuel chamber 75 and discharged into the mixing chamber in two distinct streams.

2. In a carburetor, a mixing chamber provided with a venturi, a pair of suction multiplying Venturi tubes projecting transversely of and into said venturi and forming the primary air inlet of said carburetor, a fuel chamber, a passage therefrom interconnecting the fuel chamber and the throats of said Venturi tubes whereby fuel may be withdrawn from the fuel chamber into the primary air stream of said pair of tubes and discharged in said mixing chamber, in two distinct streams.

3. In a carburetor, a mixing chamber, a pair of suction multiplying Venturi tubes disposed transversely in said chamber, said tubes having air intake ends exposed to atmosphere and discharge ends which project downwardly into said chamber and are located therein to supply a mixture of air and fuel in said chamber, a fuel chamber, a passage therefrom connecting the fuel chamber and throats of said Venturi tubes whereby fuel may be withdrawn from the fuel chamber into the air stream of said Venturi tubes and discharged in said mixing chamber in two distinct primary streams.

4. In a carburetor, a mixing chamber having a Venturi restriction, a pair of spaced suction multiplying Venturi tubes projecting transversely of and into said mixing chamber at said restriction to provide a primary inlet for said carburetor, said Venturi tubes being arranged vertically so as to discharge downwardly and being located symmetrically with respect to a vertical diameter of the chamber, a fuel chamber, a passage therefrom connecting the fuel chamber and the respective throats of the Venturi tubes whereby fuel may be withdrawn from the fuel chamber into the primary air streams passing through the Venturi tubes and discharged into said mixing chamber in two distinct streams.

5. In a carburetor, a mixing chamber provided with a venturi, a pair of suction multiplying Venturi tubes projecting transversely of and in the same vertical plane into said chamber to form a primary air inlet for said

carburetor and adapted to discharge into said venturi, a secondary air inlet for said carburetor, means governing the flow of the secondary air stream into said chamber, a fuel chamber, a passage therefrom connecting the fuel chamber and the throats of the Venturi tubes whereby fuel may be withdrawn from the fuel chamber into the respective air streams of the Venturi tubes and discharged into the secondary air stream in two distinct streams.

6. In a carburetor, a mixing chamber, a pair of spaced suction multiplying Venturi tubes disposed transversely in said chamber, said tubes having intake ends exposed to atmosphere and discharge ends located within said chamber to supply a primary mixture of air and fuel in said chamber, said tubes being located symmetrically with respect to a vertical diameter of the mixing chamber, a secondary air inlet for said carburetor, a fuel chamber, a passage therefrom connecting the fuel chamber and the throats of the Venturi tubes whereby fuel may be withdrawn from the chamber into the respective primary air streams of the Venturi tubes and discharged into the secondary air stream and at right angles thereto.

7. In a carburetor, a mixing chamber provided with a Venturi restriction, a pair of spaced suction multiplying Venturi tubes projecting transversely of and in the same vertical plane into said chamber for a substantial distance, said tubes forming a pair of primary air inlets for said carburetor, a secondary air passage for said carburetor, a fuel chamber, a passage from said fuel chamber connecting the fuel chamber and respective throats of said Venturi tubes, discharge nozzles for said Venturi tubes subjected to mixing chamber depression whereby fuel may be drawn from said fuel chamber and fed in like amounts through said passage into the respective primary air streams and discharged through said nozzles into the secondary air passage in two distinct streams at right angles thereto.

8. In a carburetor, a mixing chamber extending substantially horizontally therethrough and provided with a venturi, a pair of suction multiplying Venturi tubes substantially vertically disposed and arranged to deliver two distinct and separate primary air streams downwardly into the mixing chamber, a fuel chamber at positions within said venturi, means for maintaining a substantially constant fuel level slightly below the throats of the Venturi tubes and a passage extending from the fuel chamber to the throats of the Venturi tubes.

9. In a carburetor, a mixing chamber extending substantially horizontally therethrough, and provided with a Venturi, a pair of suction multiplying Venturi tubes substantially vertically disposed and arranged

to deliver two distinct and separate primary air streams downwardly into the mixing chamber, a fuel chamber at positions within said venturi, and a passage extending from the fuel chamber to the throats of the Venturi tubes.

In witness whereof, I hereunto subscribe my name this 18th day of February, 1931.

CERTIFICATE OF CORRECTION.

Patent No. 1,905,435.

April 25, 1933.

ROBERT F. BRACKE.

It is hereby certified that error appears in the printed specification of the above numbered patent requiring correction as follows: Page 4, lines 55 and 68, claims 8 and 9, respectively, strike out the comma and words ", a fuel chamber", and in lines 56 and 69, after "venturi," insert the words "a fuel chamber,"; and that the said Letters Patent should be read with these corrections therein that the same may conform to the record of the case in the Patent Office.

Signed and sealed this 18th day of July, A. D. 1933.

M. J. Moore.

(Seal)

Acting Commissioner of Patents.
